UNITED STATES PATENT OFFICE.

JAMES B. WILLIAMSON, OF EVERETT, MASSACHUSETTS.

DISPLAY-EASEL.

1,109,561.

Specification of Letters Patent. Patented Sept. 1, 1914.

Application filed October 23, 1913. Serial No. 796,944.

To all whom it may concern:

Be it known that I, JAMES B. WILLIAMSON, a citizen of the United States, and a resident of Everett, in the county of Middlesex and Commonwealth of Massachusetts, have invented certain new and useful Improvements in Display-Easels, of which the following is a full and exact description.

The object of this invention is the construction of a support or easel upon which bottles of medicine, post cards and other articles can be displayed, which easel shall be attractive in appearance, inexpensive to manufacture and capable of being shipped flat and of being easily put together for use.

For rendering the display easel inexpensive, and easily put together, I prefer to die it out from a single sheet of card-board, with all the lines scored along which the folds will come, and the slits cut by which the parts will be secured together.

Referring to the drawings forming part of this specification, Figure 1 is a perspective view of the display easel put together and ready for use. Fig. 2 is a central vertical section of the same on the line X—X in Fig. 1. Fig. 3 is a detail view illustrative of the formation of one of the ornamental features thereof. Fig. 4 is a face view of the display easel in its flat or knock-down form. Figs. 5 and 6 are perspective views illustrating a further improvement.

The easel comprises a back 1, sides 2 adapted by lines of scorings 3 to be readily bent at an obtuse angle with the back, and several other parts having lines of scorings parallel with the top and bottom edges of the back, to compose the shelves of the easel, 40 and the supporting members therefor. Bent down from the top edge of the back 1 along the scored line 4, is the upper frontal member 5, shown more clearly in Fig. 2, and bent horizontally forward from said member on the scored line 6 is the top shelf 7, the lateral edges of which fit against the inner surfaces of the sides 2, and are hence oblique. This top shelf is supported at its rear by said member 5, and at its front edge by the upright 9 which is bent down therefrom on the scored line 10, said upright having slits 11 adapted to coact with the slits 12 in the sides 2.

The second shelf 13 is in its turn supported at its rear edge by said upright, being bent out horizontally therefrom on the

scored line 14, and having its lateral edges parallel with the lateral edges of said shelf 7. This second shelf I prefer to provide with a frontal rim 15, which is bent up therefrom on the second line 16, the upright 17 being bent down from said rim on the scored line 19 and formed with slits 20 adapted to coact with the slits 21 in the sides 2.

The bottom shelf 22 is bent forward horizontally on the scored line 23, and has its front edge more or less curved for the sake of attractiveness in appearance, for which purpose it is cut entirely separate from the base upright 24, except for the short, central scored line 25. This base upright is formed with slits 26 for coacting with the slits 27 in the sides 2. When said slits are put into engagement, said base upright is curved back somewhat, as shown in Fig. 1, until portions of its top edge come beneath the outjutting portions 29 of the shelf 22 and aid in supporting the latter, at the same time thereby adding to the ornamental appearance of the easel, and increasing the shelf-area.

While the structure as thus far described composes a good and effective display easel, I prefer to add to its attractiveness of appearance by means of an ornamentation which will break up more or less of the horizontal lines of the easel, and thereby any possible stiffness in design will be removed. In accomplishing this, I cut out or away from certain parts of the structure small portions thereof at one side of a scored line, so that when such part or parts are bent away from the adjacent part, said small portions will stand up clear and unbroken from said adjacent part. For instance, the upper frontal member or upright 5 is not entirely separated from the back by the scored line 4, but the latter is interrupted by two irregular lines 30 cut entirely through the card board in the back 1, so that when the upright is bent down flat against the front of the back, the portions of the card board beneath said cut lines stand up above the top edges of the back 100 and upright, leaving equal holes in the back. These portions 30 being shaped to take the outline of flowers or other fanciful object which may be pictured upon the face of the card board, as shown in Fig. 1, the appearance of the easel is made exceedingly ornate.

As shown in Fig. 2, the shelf 13 is formed

- with a frontal rim 15. This frontal rim I sometimes make considerably higher, as shown in Fig. 5, and through both it and the upright 17 are openings 32 through 5 which to view the labels or other portions of bottles stood upon said shelf. To keep the edges of the rear opening hidden, I prefer to make the rear opening 32^a larger than the outer opening 32^b, as indicated in Fig. 6.
- 10 A part or parts of such rim can be cut away bodily, as at the left end in Fig. 5, for the purpose of exposing entirely some of the bottles, while partially covering more or less of the others.
- 15 What I claim is:
- A display easel composed of a single sheet of card board scored, cut and bent to form a substantially rectangular back, substantially triangular sides integral with the lateral 20 edges of the back, each side having a plurality of vertical slits, a front integral with the top edge of said back and of equal width and depending vertically therefrom, a shelf

integral with the lower edge of said front and supported thereby thereat, an upright 25 integral with said shelf at the latter's front edge, said upright being longer than said shelf and having vertical slits near its ends, the slits in said upright being put into engagement with certain slits in said triangular sides, another shelf integral with the lower edge of said upright, and another upright integral with the front edge of said shelf, the latter upright being also longer than its connected shelf and formed with 30 slits near its ends put into engagement with certain of the vertical slits in said triangular sides.

In testimony that I claim the foregoing invention, I have hereunto set my hand this 40 17th day of October, 1913.

JAMES B. WILLIAMSON.
